16 Claims. (Cl. 315—169)

The present invention relates generally to two-dimensional displays, and more particularly to two-dimensional displays produced by two groups of conductors, the conductors of one group intersecting the conductors of the other group, and the intersecting points of conductor pairs selected from the separate groups being provided with voltage sensitive material.

Briefly describing the present invention, I utilize (in a preferred embodiment) a first group of conductors which are spaced one from the other and extend parallel to one another. I further utilize a second group of conductors which are similarly spaced and similarly extend parallel to one another, the conductors of one group being located underneath the conductors of the other group in spaced intersecting relation. In the space at the points of intersection of the conductors, and located therebetween, is provided a voltage sensitive material which may be specifically electroluminescent phosphor, or voltage sensitive recording paper of the type commonly known as Teledeltos.

It is known that Teledeltos paper will provide no recording unless the applied voltage is greater than a predetermined value. Similarly, electroluminescent phosphor has the property that unless voltage of at least predetermined magnitude is applied, at any predetermined frequency, the phosphor will not glow substantially.

In accordance with the present invention signals are selectively applied to the conductors of one group in accordance with the frequencies of the signals, and also to the conductors of the other group in accordance with further frequencies. The signals applied to the conductors are amplitude limited, to assure that any signal applied to any one conductor, in the absence of a further signal applied to an intersecting conductor, will produce no visual response. Since the process of amplitude limiting results in the generation of harmonics the outputs of the amplitude limiters employed in the practice of the invention are filtered to eliminate such harmonics. Upon the application to a pair of intersecting conductors of simultaneous A.C. voltages, the sum of the voltages intermittently is sufficient to actuate the visual indicating substance or material at the point of intersection, resulting in a visual display at the point of intersection.

The selection of conductors between the groups of conductors may be accomplished by connecting in series with each conductor a crystal tuned to a selected frequency. The separate groups of crystals may be relatively widely divergent with respect to frequency, while the crystals within a group may be relatively close in frequency.

The voltage variation applied to any conductor may be amplified by connecting that conductor across one element of a resonant circuit. Preferably, to accomplish this, each crystal may be connected in series with a tuning condenser and a tuning coil, the conductor being connected intermediate the condenser and tuning coil, so that the resonant voltage rise across the tuning coil will be imparted to the entire conductor.

By virtue of the fact that the frequencies applied to the conductors of any one group are adjacent, it is feasible to utilize a single tuning coil for an entire group of conductors, or, in the alternative, to utilize a single tuning condenser for an entire group of conductors, provided that in the first case one tuning condenser is connected in series with each conductor, and in the second case one tuning coil is connected in series with each of the conductors.

2

It is, accordingly, a broad object of my invention to provide a novel display system of the frequency sensitive type.

It is a further object of my invention to provide a novel two-dimensional display.

It is another object of my invention to provide a display in terms of crossed groups of conductors, which are selectively energized by connecting the separate conductors in series with piezo-electric crystals tuned to different frequencies.

Still a further object of the present invention resides in the provision of a group of conductors which may be selected individually, or in any desired arrangement or combination, by applying suitably selected frequencies to suitable piezo-electric elements in series with the separate conductors.

Another object of the present invention resides in the provision of means for resonantly varying the voltage of an extended conductor by connecting the conductor in series between a tuning condenser and a tuning inductance which are connected in series with a source of voltage, to which the combination of condenser and inductance is series resonant.

The above and still further objects, features, and advantages of the present invention will become apparent upon consideration of the following detailed disclosure, especially when taken in conjunction with the accompanying drawings, wherein:

FIGURE 1 is a schematic circuit diagram of a circuit capable of exciting a voltage sensitive element upon the application of two selected frequencies simultaneously;

FIGURE 2 is a schematic circuit diagram of a matrix system for providing a two-dimensional display, in response to the application of preselected control frequencies;

FIGURE 3 is a modification of the system of FIGURE 2 which may be utilized when closely adjacent frequencies are utilized to excite the elements of the matrix;

FIGURE 4 is a view showing the application of the present invention to electroluminescent material, the latter providing a visual display upon the application of suitable voltages to selected conductors; and

FIGURE 5 is a modification of the system of FIGURE 4 in which Teledeltos paper is substituted for the electroluminescent material of FIGURE 4.

Referring now more particularly to FIGURE 1 of the accompanying drawings, the reference numeral 1 denotes a piezoelectric crystal tuned to a frequency f_1 while the reference numeral 2 denotes a piezo-electric crystal tuned to a different frequency f_2 . The piezo-electric crystal 1 is in series with a terminal 3 to which signal of various frequencies may be applied, these frequencies including the frequency f_1 . Similarly, the piezo-electric crystal 2 is connected in series with a terminal 4 to which may be applied various frequencies including the frequency f_2 . The crystal 1 is further connected in series with a tuning condenser 5 and a tuning coil 6, the combination of condenser 5 and inductance 6 being resonant to the same frequency as is the crystal 1. Similarly, the crystal 2 is connected in series with a tuning condenser 7 and an inductance coil 8, the latter two elements being resonant to the same frequency as the crystal 2. The electroluminescent phosphor condenser 9 is connected across the coils 6 and 8.

Upon the application of frequency f_1 to terminal 3 and of frequency f_2 to terminal 4, current flows through the crystals 1 and 2, and excites the resonant circuits 5, 6, 7, and 8. Accordingly, the voltage across the coil 6 and the voltage across the coil 8 vary at the frequencies f_1 and f_2 , and in amplitude exceed the applied voltage by the Q factors of the coils 6 and 8. The electro-

luminescent phosphor 9 is selected to have a minimum voltage threshold below which the phosphor does not glow appreciably. This voltage may be called "firing voltage." Such phosphors are well known and have been described in an article by Zalm et al., entitled "Electroluminescent ZnS Phosphors," published in Philips Research Reports, April 1954, pages 81-108. The circuit is so designed, and the voltage amplitude applied to the terminals 3 and 4 are so selected, that upon the application of only one of the frequencies f_1 , f_2 the voltage with respect to ground which exists across the electroluminescent condenser 9 is less than firing voltage. Upon the application of voltages to both terminals 3 and 4, the sum of the two voltages periodically exceeds that required to fire the phosphor condenser 9, and accordingly a glow is produced. It follows that on the application of one only of frequencies f_1 , f_2 to the system, no glow appears at the electroluminescent condenser 9, while in the presence of frequencies f_1 and f_2 simultaneously such a glow does appear. It will be apparent that in substitution of the electroluminescent phosphor 9 may be utilized voltage sensitive recording paper (Teledeltos), or other voltage sensitive material.

Reference is now made to FIGURE 2 of the accompanying drawings, wherein is shown a two-dimensional display device utilizing the principles established in FIGURE 1 of the accompanying drawings. In FIGURE 2 the reference numeral 10 denotes an amplitude limiter, which limits to a preselected value the amplitudes of signals applied to a terminal 11. Similarly, the amplitude limiter 12 limits the amplitude of signals applied to a terminal 13. It is well known that the outputs of amplitude limiters contain signals of frequencies harmonically related to those at the inputs. Accordingly, the output of the amplitude limiter 10 is filtered by filter 14 and the output of the amplitude limiter 12 by the filter 15, it being the function of the filters 14 and 15 to remove harmonic responses which were generated by the amplitude limiters 10 and 12. This is normally readily feasible, provided the band of frequencies applied to the terminals 11 and 13, respectively, are not unduly broad. As the description proceeds it will become evident that it is not required in the present system to utilize wide bands of frequencies.

Assuming now that the outputs of the filters 14, 15 contain only sinusoidal waves, within a predetermined band of frequencies, and that these waves are all of the same amplitude, the output of the filter 14 is applied to a terminal 16 and the output of the filter 15 to a terminal 17. The terminal 15 is connected in series with a plurality of piezo-electric crystals 18 to 23, inclusive, all in parallel. A terminal 17 likewise provides signal in parallel to a plurality of piezo-electric crystals 24 to 29 inclusive. The crystals 18 to 23 are separated relatively narrowly in frequency, and are responsive individually to frequencies provided at the terminal 16. Likewise the crystals 24 to 29 are individually slightly separated from one another in frequency, but all fall, in respect to resonant frequency, within the band of frequencies applied to terminal 17. Selectivity curves of crystals of adjacent frequency may overlap slightly if desired (or at 3 db down points of the curves), or may be so separated that substantially no overlap occurs. The system will be operative in either event.

Considering the crystal 18 as typical, it is connected in series with a tuning condenser 30, an elongated conductor 31 and a tuning coil 32, the latter proceeding to ground or other reference point. The condenser 30 and the tuning coil 32 form a series resonant circuit, which is resonant to the same frequency as the piezo-electric crystal 18. Accordingly, the voltage across the tuning coil 32, or the voltage across the conductor 31, with respect to ground, varies in amplitude at the frequency which the crystal 18 passes, but the amplitude variation

is in excess of that applied at the terminal 16 by virtue of the resonant rise across the tuning coil 32. This resonant rise may be of the order of thirty or more times, depending upon the value of Q of the coil 32.

Located adjacent to the elongated conductor 31 are further conductors 32, 33, 34, 35, 36 which are separated from the conductor 31, so as to be insulated therefrom and which extend parallel thereto. A similar group of conductors 37 to 42, inclusive, extend at right angles to the conductors 31 to 36, and are separated with respect to one another by about the same spacing as are the adjacent conductors 31 to 36, respectively. The various conductors are individually connected just as is the conductor 31, being provided each with a tuning coil and a tuning condenser, and accordingly the arrangement and connections of the individual conductors are not further described herein.

The groups of conductors 31 to 36 and 37 to 42 extend in mutually perpendicular directions, although other relative angles may be selected, and if desired one of the groups may extend circumferentially while the other group extends radially. In any event, points of intersection occur between individual conductors of the two separate groups. At the points of intersection the conductors are slightly separated, and in the space between the conductor pairs is inserted electroluminescent material, as 44, or voltage sensitive recording paper, as 45, of the type commonly sold commercially under the trade name Teledeltos. The electroluminescent material and the Teledeltos paper are merely examples of voltage sensitive materials which have minimum thresholds below which applied voltage will not cause a visual response, and above which such a response will occur. In the case of electroluminescent material the response point may be adjacent to the value 40 volts, while in the case of Teledeltos paper the value may be considerably lower. In any event such a minimum threshold does exist in either case, and materials cannot be employed in the practice of the present invention which do not possess such minimum thresholds.

The amplitude values provide at the terminals 16 and 17 are such, and the Q values of the resonant circuits employed are such, the term resonant circuits referring to combination of condenser and tuning coils such as 30, 32, 45 for example, that application of voltage to an element of one group of conductors in the absence of voltage applied to an intersecting conductor does not cause a visual display. Only upon the application of simultaneous voltages to two intersecting conductors does a visual display occur at the point of intersection of the conductors. Accordingly, a visual display point may be caused to occur at any point in two dimensions, by selecting the frequencies applied to the terminals 16 and 17 so as to cause simultaneous current flow through one crystal of the set 18 to 23 inclusive and one crystal of the set 24 to 29 inclusive. It will be apparent that any number of piezo-electric crystals from the separate groups of crystals may be simultaneously excited by applying a group of frequencies to the terminals 16 and 17. Accordingly, all the intersection points of the two-dimensional display may be caused to provide visual responses simultaneously, or any one or combination of intersection points may be energized.

The system of FIGURE 3 is generally similar to that of FIGURE 2, except in that a single inductance coil 50 is employed in conjunction with one group of conductors 31 to 36, and a single tuning coil 51 in conjunction with the intersecting group of conductors 37 to 42, respectively. This procedure is rendered possible if the piezo-electric elements 18 to 23 are sufficiently close in frequency, and similarly if the piezo-electric elements 24 to 29 are sufficiently close in frequency. In practice this will usually be found to be the case.

While I have shown a condenser 30 in series with a tuning coil 50, it will be apparent to those skilled in the

electrical arts that separate tuning coils may be applied in series with each of the conductors 31 to 36, and a single tuning condenser be connected jointly to all conductors to ground, in place of the alternative arrangement. Similarly, in connection with conductors 37 to 42 a single condenser may be employed in substitution of coil 51, provided a plurality of tuning coils are employed in place of associated series condenser.

While I have described and illustrated one specific example of the present invention, it will be clear that variations of the specific details of construction may be resorted to without departing from the true spirit of the invention as defined in the appended claims.

What I claim is:

1. A device for providing two-dimensional displays, comprising at least one elongated conductive element, at least another elongated conductive element, said elongated elements positioned to intersect each other, voltage sensitive material located intermediate said elongated elements at their intersection, a piezo-electric crystal tuned to one frequency connected in series with one of said elements, a piezoelectric crystal tuned to another frequency connected in series with the other of said elements, a separate tuning series condenser and tuning coil pair connected in series with each of said elements, each condenser and tuning coil pair resonant to the frequency of one of said piezo-electric crystals.

2. In a two-dimensional display, a first plurality of separated conductors extending in a first coordinate, a second plurality of separated conductors extending in a second coordinate, and all intersecting said first plurality of separated conductors to form cross-over points, voltage sensitive visualizing material located at least intermediate the cross-over points of said conductors, a piezoelectric crystal connected in series with each of said conductors, each of said crystals tuned to a different frequency, and means for applying signals to said crystals at amplitudes such that only concurrent application of voltage to two conductors at a cross-over point thereof will effect visualizing response of said voltage sensitive visualizing material, said voltage sensitive visualizing material having a response threshold in response to applied voltage below which no substantial response occurs.

3. The combination in accordance with claim 2, wherein is provided means for causing the voltage of each of said conductors to vary resonantly with respect to a reference value, said last means including means for including each of said conductors across one element of a resonant circuit.

4. A device for providing two-dimensional displays, comprising at least one elongated conductive element, at least another elongated conductive element, said elongated elements positioned to intersect each other, voltage sensitive material located intermediate said elongated elements at their intersection, a pass filter tuned to one frequency connected in series with one of said elements, a pass filter tuned to another frequency connected in series with the other of said elements, a separate tuning series condenser and tuning coil pair connected in series with each of said elements, each condenser and tuning coil pair resonant to the frequency of one of said pass filters.

5. In a two-dimensional display, a first plurality of separated conductors extending in a first coordinate, a second plurality of separated conductors extending in a second coordinate, and all intersecting said first plurality of separated conductors to form cross-over points, voltage sensitive visualizing material located at least intermediate the cross-over points of said conductors, a series resonant filter connected in series with each of said conductors, each of said filters tuned to a different frequency, and means for applying signals to said filters at amplitudes such that only concurrent application of voltage to two conductors at a cross-over point thereof will effect visualizing response of said voltage sensitive visualizing ma-

terial, said voltage sensitive visualizing material having a response threshold in response to applied voltage below which no substantial response occurs.

6. The combination in accordance with claim 5, wherein is provided means for causing the voltage of each of said conductors to vary resonantly with respect to a reference value, said last means including means for including each of said conductors across one element of a resonant circuit.

7. In a system for generating a visual display in response to two frequencies simultaneously, an electro-sensitive visual display device having two electrodes, said device having a predetermined minimum voltage for which a display is generated, a first series resonant circuit tuned to one of said two frequencies, a second series resonant circuit tuned to the other of said two frequencies, each of said series resonant circuits including a tuning inductance and a tuning capacitor, and means connecting said electrodes to the junction of said tuning inductances and capacitors.

8. In a system for generating a visual indication in response only to signals at predetermined frequencies, an electro-sensitive display device having two electrodes, between which subsists electro-sensitive material, means comprising a first filter tuned to one of said frequencies for applying alternating voltage with respect to a point of reference potential to one of said electrodes, and means comprising a second filter tuned to the other of said frequencies for applying an alternating voltage with respect to said point of reference potential to the other of said electrodes.

9. In a system for generating a visual indication in an electro-sensitive medium, a pair of electrodes between which said electro-sensitive medium subsists, a terminal, a circuit having reactance of one sign connected between one electrode of said pair and said terminal, a circuit having reactance of one sign connected between the other electrode of said pair and said terminal, and means resonating with each of said circuits so associated with said circuits that resonant rises in voltage occur at said terminals.

10. A system for generating a variation of condition in an electro-sensitive device, said device having terminals, in response only to simultaneous occurrence of a predetermined pair of frequencies, comprising means for effecting a resonant rise in voltage for one of said terminals in response to one of said frequencies, and means for effecting a resonant rise in voltage in the other of said terminals in response to the other of said frequencies.

11. In a system for generating a visual display in response to two frequencies simultaneously, an electro-sensitive visual display device having two electrodes, said device having a predetermined minimum voltage for which a display is generated, a first series resonant circuit tuned to one of said two frequencies, a second circuit, said resonant circuit including an inductance and a capacitance, means connecting one of said electrodes to the junction of said inductance and capacitance, means connecting the other of said electrodes to a terminal of said second circuit, means for supplying signal to said resonant circuit at the resonant frequency of said resonant circuit, and means for applying A.C. signal to said second circuit, the sum of the amplitudes of said signals being selected to equal at least said predetermined minimum voltage, and said signals individually having less than said predetermined minimum voltage.

12. A system for applying signal selectively to the electrodes of a voltage sensitive indicator, comprising a series resonant circuit including an inductance and a capacitance, and means connecting said voltage sensitive indicator across one of said inductance and said capacitance only.

13. An electronic circuit for the excitation of a series of electroluminescent elements comprising an electronic control circuit adapted to receive a burst of energy, said

control circuit being operatively associated with a plurality of driver circuits, and a resonant circuit operatively associated with each of said driver circuits, said resonant circuits each including an electroluminescent element.

14. An electronic circuit for the excitation of a plurality of electroluminescent elements comprising an input circuit adapted to receive wave energy, a plurality of further circuits coupled in parallel to said input circuit, and a resonant circuit associated with each of said further circuits, said resonant circuits each including at least one electroluminescent element.

15. The combination according to claim 14, wherein each of said resonant circuits is tuned to respond to a different frequency component of said wave energy.

16. The combination according to claim 15, wherein each of said further circuits includes a resonant circuit.
